UNITED STATES PATENT OFFICE
CERTIFICATE OF CORRECTION

Design No.184,507

March 3, 1959

James F. G. Bowlby

It is hereby certified that error appears in the above numbered patent requiring correction and that the said Letters Patent should read as corrected below.

In the grant, lines 1, 2 and 3, for "James F. G. Bowlby, of Butler, New Jersey," read -- James F. G. Bowlby, of Butler, New Jersey, assignor to Century Enterprises, Inc., of New York, N. Y., a corporation of New York, --; line 12, for "James F. G. Bowlby, his heirs" read -- Century Enterprises, Inc., its successors --; in the heading to the drawings and printed specification, line 3, for "James F. G. Bowlby, Butler, N. J." read -- James F. G. Bowlby, Butler, N. J., assignor to Century Enterprises, Inc., New York, N. Y., a corporation of New York --.

Signed and sealed this 21st day of July 1959.

(SEAL)
